US00D516399S

(12) United States Design Patent (10) Patent No.: US D516,399 S
Oide (45) Date of Patent: * Mar. 7, 2006

(54) PORTABLE HYDRAULIC SPREADER DEVICE

(75) Inventor: Eisuke Oide, Yokohama (JP)

(73) Assignee: Kabushiki Kaisha Ogura, Ebina (JP)

() Term: 14 Years

(21) Appl. No.: 29/182,146

(22) Filed: May 20, 2003

(30) Foreign Application Priority Data

Nov. 26, 2002 (JP) 2002-032634

(51) LOC (8) Cl. 08-05

(52) U.S. Cl. D8/68

(58) Field of Classification Search ..... D8/14.1, D8/61, 62, 63, 64, 65, 66, 67, 68, 69, 70; 81/57.11, 429, 464, 465, 466, 469, 489; 173/13, 173/169, 178, 213, 217; 227/8, 114, 120, 227/130, 136, 142; 310/50; 408/20, 124, 408/125, 234, 241 R; 451/358; D15/127

(57) CLAIM

The design for the portable hydraulic spreader device, as shown.

DESCRIPTION

FIG. 1 is a perspective view of the portable hydraulic spreader device;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.
